(57) CLAIM

The ornamental design for an automobile grille, as shown and described.

DESCRIPTION

FIG. 1 is a perspective view of an automobile grille showing my new design;

FIG. 2 is a front elevation view thereof;

FIG. 3 is a top plan view thereof; and,

FIG. 4 is a right side elevation view thereof.

The broken lines in the drawings are provided for the purpose of illustrating portions of the automobile grille that form no part of the claimed design.
